Assistant Examiner — Mary Anne Arntzen

(57) **CLAIM**

The ornamental design for a water timer as shown and described.

DESCRIPTION

FIG. 1 is a front, right perspective view of a first embodiment of the water timer showing my new design;

FIG. 2 is rear, left perspective view of FIG. 1

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is a front, right perspective view of a second embodiment of the water timer;

FIG. 10 is rear, left perspective view of FIG. 9;

FIG. 11 is a front view of FIG. 9;

FIG. 12 is a rear view of FIG. 9;

FIG. 13 is a left view of FIG. 9;

FIG. 14 is a right view of FIG. 9;

FIG. 15 is a top view of FIG. 9; and,

FIG. 16 is a bottom view of FIG. 9.
